WELTING FOR USE IN THE MANUFACTURE
OF SHOES

George Goddu, Winchester, Mass., assignor to
United Shoe Machinery Corporation, Paterson,
N. J., a corporation of New Jersey

Application February 29, 1932, Serial No. 595,799

6 Claims. (Cl. 36—78)

This invention relates to improvements in welt-
ing and is illustrated herein with respect to the
manufacture of welted shoes having cement at-
tached soles.

5 In cement attaching soles to shoes it is usual
to engage the sole by means of a pad containing
a suitable fluid, such as air or water, while the
toe portion of the shoe and the cone of the last
on which the shoe is being made are supported
10 by suitable abutments. The sole attaching pres-
sure is either applied by or involves increasing
the pressure of the fluid within the pad and this
causes the exposed surface of the sole engaging
wall of the pad to bulge, thereby tending to wrap
15 the portion of the sole which extends beyond the
last bottom into engagement with the shoe upper
and producing the so-called "rolled edge" effect.
While this appearance is desired in the manu-
facture of some styles of shoes there are other
20 styles and types, among which are most welt
shoes, in which the transversely curved bottom
and the rather sharply rolled edge so produced
are usually not desired. On the contrary, a rela-
tively flat bottom is usually called for in a welt
25 shoe of any type and a flat marginal portion with
a "square" edge to the sole is demanded for
style reasons.

The invention of this application comprises
30 improved welted, particularly adapted for use in
the manufacture of shoes as disclosed in a co-
pending application, Serial No. 699,049, filed No-
vember 21, 1933, as a division of the present ap-
plication. The new welted, the upper-engaging
35 or grain surface of which is pre-cemented, prefer-
ably after it has been roughened, is particularly
useful in facilitating the obtaining of a tight,
close edge in the manufacture of welted shoes,
especially in the manufacture of welted shoes hav-
ing cement-attached soles.

40 The invention will now be described with refer-
ence to the accompanying drawing and pointed
out in the claims.

In the drawing,

45 Fig. 1 is a perspective view of an insole for use
in manufacturing shoes in accordance with the
present invention;

Fig. 2 is a sectional view on an enlarged scale
50 on the line II—II in Fig. 1, but before any rein-
forcing material has been applied to the insole;

Fig. 3 is a sectional view on the line III—III
of Fig. 1;

Fig. 4 is a transverse sectional view through
55 the forepart of a shoe in the course of manufac-
ture in accordance with my invention, showing

the condition after the completion of the lasting
operation;

Fig. 5 is a similar view after the completion
of the welted operation;

Fig. 6 is a sectional view showing the con-
struction of the shoe after the completion of the
inseam trimming and inseam pressing or rolling
operation;

Fig. 7 is a transverse section through a por-
tion of the forepart of the finished shoe;

Fig. 8 is a transverse section through the fore-
part of a shoe illustrating a step in the cement
attachment of a welt to the overlasted margin of
the shoe upper;

Fig. 9 is a sectional and perspective view of the
5 15
welted shown in Fig. 5; and

Fig. 10 illustrates welding with a portion of
its upper engaging surface coated with cement
for use in the practice of the method illustrated
20 in Fig. 8.

The insole 12, illustrated in Figs. 1, 2 and 3, is
made from a piece of leather stock of substan-
tially uniform thickness and has a lip 14 pro-
jecting upwardly therefrom. As illustrated in
25 Figs. 1 and 3, the portion of the insole inside
of the lip, as well as the inner surface of the
lip, is reinforced with a piece of duck 16 in the
manner usual in the manufacture of Economy
30 insoles. The insole is also provided with a
shoulder 18, which as best shown in Fig. 2 is con-
tinuous with the base of the lip 14 while the edge
20 of the insole is of the full thickness of the
original stock. This construction may be pro-
35 duced by removing from the peripheral portion
of the upper face of the insole a piece of stock
triangular in cross section (indicated by the space
below the dotted line 19 in Fig. 2), the apex of
the triangle lying at the corner formed by the
40 intersection of the edge surface 20 and the upper
surface 21 of the insole, its base extending height-
wise of the insole, about $\frac{1}{4}$ of an inch or there-
abouts from the edge of the insole, and its
hypotenuse being inclined from its apex into the
substance of the insole and intersecting its base
45 about half way through the insole. The lip 14
is produced by cutting an inside channel in the
usual way, with the bottom of the channel spaced
from the shoulder 18 sufficiently to leave the
necessary between-substance for the reception
50 of the stitches of the inseam. The channel flap
is then turned up, as illustrated in Fig. 2, and the
reinforcing duck 16 applied in well-known
fashion.

It may be noted here that in construing this
55

specification and the accompanying claims such words as "up", "upper", "down", "raising", etc. where applied to the insole and its parts are to be understood as applied to the parts when the insole 5 is in the position it assumes when a shoe in which it is embodied is positioned bottom upwardly.

The insole 12 is tacked to a last 22 and the shoe upper assembled and lasted as in the manufacture of Goodyear Welt shoes. In Fig. 4 the 10 upper 24 is shown as secured in lasted relation by means of staples 26 driven through the marginal portion of the shoe upper 24 and the lip 14 of the insole 12, the staples being clenched on the inner surface of the lip. This may be done, 15 for example, with a side lasting machine of the character illustrated in Letters Patent of the United States No. 1,796,451, granted March 17, 1931, on an application filed in the name of George Goddu. The toe and heel ends of the 20 shoe may be lasted in any usual or preferred manner.

After the lasting the welt 28 is stitched to the marginal portion of the shoe upper and to the lip 14 of the insole by an inseam 30, as in the 25 manufacture of Goodyear Welt shoes. This welt should be both light and narrow, and is preferably of a wedge formation, as clearly shown in Fig. 9. The welt may be, for example, $\frac{1}{8}$ of an inch wide and about $\frac{1}{20}$ of an inch thick at its 30 inner edge and thinned down almost to a feather at its outer edge. Preferably the welt is provided with a shallow groove 29 for the reception of the stitches of the inseam at its inner edge.

The inseaming operation will pull the shoe 35 upper and the welt well down into the angle at the base of the shoulder of the insole, as shown in Fig. 5, so that after the inseam has been trimmed and pounded or rolled, for example with the well-known automatic leveling machine commonly used for leveling the soles of Goodyear 40 Welt shoes, the sole receiving surface of the welt 28, together with the edge surface of the marginal portion of the shoe upper and the inseam produced by the inseam trimming operation, are 45 flat and substantially in the plane of the surface of the insole. This is well shown in Fig. 6. The welt 28, moreover, extends but slightly beyond the shoe upper so that there is little tendency for it to yield under the sole attaching pressure. 50 Plastic filler 32 (Fig. 7) is applied sparingly to the shoe bottom, it being desirable to do little more than to fill the "gutter" formed by the lifting of the insole lip 14.

The sole receiving surface of the welt 18 and 55 the edge surfaces of the shoe upper and insole lip (indicated at 31 in Fig. 6) are then roughened and coated with a cellulose derivative cement such as pyroxylin cement which is allowed to dry. The marginal portion of a sole 34 is also 60 roughened, first having been reduced in thickness if desired, and is coated with similar cement which is also allowed to dry. The dry cement on the sole (and if desired on the shoe bottom also) is activated with a suitable solvent or softener. 65 Then the sole 34 is applied to the shoe and the shoe and sole are put under pressure, for example in a cement sole attaching machine of the character disclosed in Letters Patent of the United States No. 1,897,105, granted February 70 14, 1933, on an application filed in the name of Milton H. Ballard. After the cement has set to form the permanent sole attaching means the shoe is taken from the pressure applying apparatus and is finished in the usual way. Since the 75 sole and welt have not been rolled up about the

shoe upper the shoe may be edge trimmed with a substantially "square" edge to the sole and the marginal portion of the sole will be substantially flat as it is in a Goodyear Welt or a turn shoe. The sole may be edge trimmed closer than a Goodyear Welt shoe (see Fig. 7) as there are no 5 sole attaching stitches to look out for.

If desired the welt 28 may be cemented to the shoe upper thus providing a particularly strong construction and aiding materially in maintaining the desired edge effect without affecting the appearance of the shoe. If this is to be done the overlasted portion of the shoe upper is roughened, for example after the lasting operation, the roughened portion extending peripherally of the 15 shoe bottom and being that portion indicated by the reference character 40 in Fig. 4. This may be done with the aid of a rotating wire brush or any other suitable implement. The welt which is to be used in such a shoe has its upper engaging 20 surface roughened and coated with pyroxylin cement, as illustrated at 42 in Fig. 10, over perhaps $\frac{3}{4}$ of its area, extending from its inner edge and opposite the stitch receiving groove. After the welt has been attached to a shoe, the inseam 25 trimmed, and the bottom of the shoe otherwise prepared for the reception of the sole, the welt is lifted slightly, as shown in Fig. 8, and the cement 42 on its upper-engaging surface is activated with cement softener. When the sole is cemented 30 attached, as heretofore described, the sole attaching pressure serves not only to press the sole forcibly against the shoe bottom but also to press the welt against the overlasted margin of the 35 shoe upper so that when the sole attaching pressure is relieved the welt will be firmly cemented to the shoe upper.

Having described my invention, what I claim as new and desire to secure by Letters Patent of the United States is:

1. Welting having one of its surfaces provided with a stitch receiving groove adjacent to the edge of the welting, and the portion of the opposite surface adjacent to the same edge roughened and provided with a coat of pyroxylin cement.

2. Wedge welting provided with a stitch receiving groove on one of its faces adjacent to the thick edge of the welting, and having the portion of the opposite faces adjacent to the thick edge 50 of the welting roughened and provided with a coat of dry pyroxylin cement.

3. Leather welting having a grain surface a portion of which is roughened and provided with a coat of dry cement.

4. Leather welting having a portion of one of its flat faces provided with a coat of dry cement, the remainder of that face being the grain of the leather and free from cement.

5. Leather welting having a flesh surface provided with a stitch receiving groove adjacent to an edge of the welting and a grain surface opposite the flesh surface, the portion of the grain surface adjacent to said edge of the welting being roughened and provided with a coat of dry 65 pyroxylin cement.

6. Leather wedge welting having a flesh surface provided with a stitch receiving groove adjacent to the thick edge of the welting and a grain surface opposite the flesh surface, the portion of the grain surface adjacent to the thick edge of the welting being provided with a coat of dry pyroxylin cement.
